UNITED STATES PATENT OFFICE.

ISAAC H. LEITER, OF NEW YORK, N. Y.

DESIGN FOR GIMP.

SPECIFICATION forming part of Design No. 17,325, dated May 10, 1887.

Application filed February 7, 1887. Serial No. 290,873. Term of patent 14 years.

To all whom it may concern:

Be it known that I, ISAAC H. LEITER, a citizen of the United States, residing in the city, county, and State of New York, have invented 5 and produced a new and original Design for Gimps, of which the following is a specification, reference being had to the accompanying drawing, forming part thereof.

My new design for gimps consists of a configuration formed of a longitudinal band running along the center of the gimp, transverse bars crossing the same at regular intervals; of a longitudinal band running along each side of the central band and near the scalloped edge 15 of the gimp, and transverse bars crossing the same at regular intervals, and a series of parallel strands running longitudinally along the gimp between the central and outer bands and slightly in advance of each other, thereby 20 giving the strands the appearance of converging toward the central band. The transverse

bars crossing the central band are slightly in advance of the transverse bars crossing the outer bands.

The drawing shows a face view of my new 25 design.

A A represent the central band; B B, the transverse bars crossing the same. C C represent the bands on each side of the central band; D D, the transverse bars crossing the same. 30 E E represent the parallel strands referred to above.

I claim—

The new design for gimp, consisting of the bands A and C C, bars B B and D D, and the 35 strands E E, forming the configuration herein shown and described.

ISAAC H. LEITER.
